CLAIM

The ornamental design for an environment measurement apparatus with wireless communication device, as shown and described.

DESCRIPTION

FIG. 1 is a front, top, and right side perspective view of an environment measurement apparatus with wireless communication device showing our new design;

FIG. 2 is a rear, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The oblique shade lines in the figures indicate translucency. The broken lines shown in the figures illustrate portions of the environment measurement apparatus with wireless communication device that form no part of the claimed design.
